CLAIM

The ornamental design for a ceiling fan blade, as shown and described.

DESCRIPTION

FIG. 1 is a top view of a ceiling fan blade showing my new design.

FIG. 2 is a bottom view thereof.

FIG. 3 is a right side view thereof, the left side view being a mirror image thereof.

FIG. 4 is a rear view thereof; and,

FIG. 5 is a front side view thereof.

The broken line showing of apertures is included for the purpose of illustrating environmental structure and forms no part of the claimed design.
